UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed March 24, 1923. Serial No. 627,263.

To all whom it may concern:

Be it known that I, ALFRED G. F. KUROWSKI, a citizen of the United States, residing in Brooklyn Borough, in the county 5 of Kings, city and State of New York, have invented certain new and useful Improvements in Typewriting Machines, of which the following is a specification.

The invention relates to typewriting machines. More particularly, the invention relates to platen-carriage-releasing devices controlled by tabulator or column stop mechanism, to the end that the carriage is released concomitantly with the setting of the 10 column or tabulator stop by the usual key-connections therefor.

In typewriting machines, the carriage is ordinarily urged in letter-feed direction by a spring-drum, and the letter-feed movement of the carriage is ordinarily controlled 20 by escapement mechanism actuated by the type-keys, and co-operating with a rack on the carriage. In certain work, such, for instance, as in tabulating, it is, however, desirable to release the carriage from the escapement mechanism, so that it may be promptly thrown by the spring-drum to desired column position; the column position being determined by a column or tabulator 25 stop set by a special key and connections therefor. The setting of the stop and the release of the carriage being concomitant actions, the stop or its operating connections have been conveniently used for releasing 30 the carriage-rack from the escapement mechanism. In the standard Underwood machine, for instance, a finger on the column or tabulator stop operates, when the stop is set, to rock a lever which lifts the carriage-rack 35 from a pinion forming part of the escapement mechanism.

It occasionally happens that, in throwing the platen-carriage to a stop, such as the right-hand marginal stop, the carriage-rack 40 is momentarily and accidentally disengaged from the escapement mechanism; so that, before re-engagement of the rack with the escapement mechanism, the carriage has slipped one or more letter-feed spaces from proper position; thereby causing irregularities in the work.

An object of the present invention is the provision of means for utilizing the column or tabulator stop, or connections therefor, to

lock the carriage-releasing means, so that 55 the rack may not be disengaged from its escapement mechanism except when the column or tabulator stop is operated; or, in other words, so that, when the column or tabulator stop is in its normal, unset position, as when the carriage is being returned to the right-hand marginal stop, accidental disengagement of the rack from its escapement mechanism will be prevented, by reason of the fact that the column or tabulator 60 stop is in such unset position.

A lever having a roll thereon, for supporting the rack in its normal or effective position, may be employed for disengaging the 65 rack from the escapement mechanism, and a finger on the column or tabulator stop employed for operating the lever to disengage the rack and release the carriage when such stop is operated.

In this construction, a feature of the present invention is the provision of a shoulder, such, for instance, as a crooked finger, on the rack-release lever, and another shoulder or finger on the tabulator-stop in the path 70 of the shoulder on the release-lever; so that, when the tabulator-stop is in unset position, the release-lever is locked by abutment of the two shoulders; and so that, in setting the stop, the shoulders are moved out of alignment to unlock the release-lever.

A further feature of the invention is the provision of means whereby a column or tabulator stop (utilized both to operate a carriage-release device when the stop is set 75 and to lock the carriage-release device when the stop is unset) operates, in one continuous movement to set position, first to unlock the carriage-release lever, and then to actuate the carriage-release lever.

Other features and advantages will hereinafter appear.

In the accompanying drawings, Figure 1 is a view, in side elevation, of so much of the mechanism of a typewriting machine as involves the present invention; 100 the tabulator-stop frame being in normal, ineffective position.

Figure 2 is a view similar to Figure 1, showing the position of the parts assumed on partial depression of the tabulator-key; 105 the safety device for holding the roll-lever being released before the movement of the tabulator-stop frame by the key has pro-

gressed far enough to release the carriage-rack.

Figure 3 is a view similar to Figures 1 and 2, showing the position assumed by the 5 parts when the tabulator-stop frame is in effective position and the carriage-rack released from its pinion.

The platen 10, on an axle 11, is journaled in the platen-frame 12 on the carriage 13, 10 mounted to have movement in letter-feed and return directions on a rail 14 on the main frame 15. The movement of the platen-carriage in letter-feed direction is effected by the usual spring-drum 15^a, the 15 strap 15^b of which is connected to the carriage; the letter-feed movement of the carriage under the action of the spring-drum being, however, controlled by dogs 16 and 17 on a dog-rocker 18, operated through 20 well-known connections (not shown), including a universal bar actuated by the type-keys. For controlling letter-space feed of the platen-carriage, the dogs 16 and 17 co-operate with an escapement wheel 19, fast 25 on a shaft with a pinion 20, adapted to be engaged by a rack 21, connected to the carriage. The rack 21 is supported on arms 22, pivoted at 23 to the sides of the carriage. These arms are adapted to be swung up to 30 lift the rack out of engagement with the pinion 20, and thereby to release the carriage from the control of the escapement mechanism, so that the carriage may be thrown by the spring-drum from one to an 35 other column or tabulating position determined by stops. When, by reason of gravity drop, the rack 21 is in engagement with the pinion 20, it rides upon and is supported by a roll 24, carried on a lever 25, pivoted 40 at 26 to the escapement-frame member 27. A stop-screw 28, threaded into an ear 29 on the lever 25, by abutment with a shoulder 30, on the frame-piece 27, determines the 45 normal position of the lever and rack-supporting roll 24. When the lever 25 is swung around its pivot 26, to lift the roll 24, from Figure 1 to Figure 3 position, the rack 21 is disengaged, as above mentioned, from the pinion 20.

50 The lever 25 is conveniently operated, to release the rack, by means of a finger 31, which is secured to a cross-piece 32 of a tabulator-stop frame 33; so that, when the tabulator-stop frame is swung in counterclockwise direction, around a pivot 34, by means of a link 35, connected to the tabulator-key lever (not shown), the finger 31, by engagement with and depression of the tail-piece 36 of the lever 25, swings the latter in a direction to throw the rack up out of engagement with the pinion 20.

55 The link 35 is pivotally connected at 37 to a tabulator-stop frame shown as of the style found in the Underwood machine. 60 Rigidly secured to the cross-bar 32 of this

frame, at each end thereof, is an arm 38, the upper ends of which are connected by a bar 39. The face 40 of the bar 39 is graduated to present a letter-space scale; and a rack 41 is formed on the under side of this 70 bar. Pivoted on, and slidably adjusted along, a shaft 42, carried by the arms 38, are the tabulator-stops, one of which 43 is shown in the drawings. The tabulator-stop is in the form of a blade, the upper edge 44 75 of which is adapted to co-operate with the teeth of the rack 41. By means of a finger-piece 45, unitary therewith, the blade may be rocked on the rod 42 to be disengaged from the rack 41; whereupon, also, by means of the finger-piece 45, the stop may be slid along the rod 42 to desired column or tabulating position, indicated by registration of a pointer 46 on the stop with the 80 graduations of the scale 40. Thereupon the stop is swung angularly forward to cause the blade to enter between the slotted teeth of the rack 41, and, by the latter, to be held against longitudinal movement on the rod 42. Suitable means (not shown) are provided for holding the stop against angular displacement from the rack 41. 85

90 With the stop in selected position on the tabulator-stop frame, it may be swung with the latter by means of the tabulator-key and link 35 from Figure 1 to Figure 3 position. In the Figure 3 position, a tooth 47 on the stop-blade 43 lies in the path of a fixed stop 48 on the carriage-frame 13. 95 When, therefore, the tabulator-stop frame is in Figure 3 position, and the carriage released to the action of the drum-spring, the fixed stop 48 on the carriage, after the predetermined throw of the latter, will 100 strike the tooth 47 of the tabulator-stop and be arrested by the latter, because the latter is held by the rack 41 against movement longitudinally of the shaft 42. The front face 49 of the bar 39, by engagement with a 105 brake-band or bar 50 on the carriage, serves to determine the forward throw of the tabulator-stop frame by the link 35, and to break the force of the throw of the carriage under the action of the drum-spring. Upon release of the tabulator-key, the tabulator-stop frame, whether by the gravity action of the rack 21, acting through the lever 25, or by other means (not shown), is returned 110 to Figure 1 position. 115

120 It has been found that, in throwing the carriage to the marginal stop at the starting position of a line, or portion of a line, the impact of the carriage against such marginal stop, may result in throwing the lever 25 with the roll 24 up in such manner as to momentarily disengage the rack 21 from the pinion 20. When the rack thereupon, by gravity, falls again into engagement with the pinion 20, the carriage may have slipped 125 a distance of one or more letter-spaces from 130

true starting position, thus causing inaccuracies in writing. For preventing such undesired action of the lever 25 and roll 24, and for preventing any movement of the 5 lever 25 with the roll 24, except when such movement is desired to disengage the rack upon operation of the tabulator-key, the lever 25 is provided with a suitable member, here shown as an upward and rearward off- 10 set finger 51, the rear end 52 of which, when the parts are in Figure 1 position, directly registers with and engages a second member, shown as a finger 53, secured to, and extending forward from, the bar 32 of the tab- 15 ulator-stop frame. The end 52 of the finger 51 is preferably beveled upward and rearward in a manner better to cause the lever 25 to be locked by the finger 53 on the tabulator-stop frame in the Figure 1 position of 20 the parts, so that the lever 25 cannot, at such time, be swung clockwise around its pivot 26 to lift the rack.

When, however, the tabulator-key, and through it the link 35, is operated to swing 25 the tabulator-stop frame in counter-clockwise direction, from Figure 1 to Figure 3 position, the finger 53 on the tabulator-stop frame, as shown in Figure 2, moves out of registration with the finger 51 on the lever 25, before the tabulator-stop tooth 47 gets into the path of the fixed stop 48 on the carriage, and before the finger 31 on the tabulator-stop frame has had occasion to release the rack by actuation of the lever 35 25 through its tail-piece 36. As depression of the tabulator-stop key is, however, continued, and, after the stop or lock fingers 51 and 53 are out of registration (so that the lever 25 is free to be swung), the tab- 40 lator-stop completes its movement to bring the tooth 47 into the path of the stop 48, and to cause the finger 31 to act upon the lever 25, to release the rack. Upon release of the tabulator-key, the parts return from 45 Figure 3 to Figure 1 position, thereby again locking the lever 25 against release with the rack.

Variations may be resorted to within the 50 scope of the invention, and portions of the improvements may be used without others.

Having thus described my invention, I claim:

1. In a typewriting machine having a platen-carriage mounted for letter-space 55 movement, a rack for said carriage, an escapement co-operative with said rack to control said carriage movement, means for disengaging said rack from said escapement to release said carriage, stop-mechanism for said carriage, said stop-mechanism including a frame having a stop movable into the path of said carriage, means for concomitantly operating said stop-mechanism and said carriage-releasing means, and 60 locking means operative directly between 65

said frame and said carriage-releasing means for normally rendering said carriage-releasing means inoperative.

2. In a typewriting machine having a platen-carriage mounted for letter-space 70 movement, a rack for said carriage, an escapement co-operative with said rack to control said carriage movement, means for disengaging said rack from said escapement to release said carriage, stop-mechanism for 75 said carriage, said stop-mechanism including a frame having a stop movable into the path of said carriage, means for concomitantly operating said stop-mechanism and said carriage-releasing means, and locking means operative directly between said frame and said carriage-releasing means for normally rendering said carriage-releasing means inoperative, said locking means being rendered inoperative during movement of 80 said stop-mechanism by said operating means, permitting release of said carriage.

3. In a typewriting machine having a platen-carriage mounted for letter-space 90 movement, a rack for said carriage, an escapement co-operative with said rack to control said carriage movement, means for disengaging said rack from said escapement to release said carriage, stop-mechanism for 95 said carriage, said stop-mechanism including a frame having a stop movable into the path of said carriage, means for concomitantly operating said stop-mechanism and said carriage-releasing means, and locking means operative directly between said frame and said carriage-releasing means for normally rendering said carriage-releasing means inoperative, said locking means comprising a plurality of co-operative members, one of said members being located in said 100 disengaging means and another being located in said frame, said members being rendered inoperative during movement of said stop-mechanism by said operating means, 105 permitting release of said carriage.

4. In a typewriting machine having a platen-carriage mounted for letter-space movement, a rack for said carriage, an escapement co-operative with said rack to control said carriage movement, a pivoted lever for disengaging said rack from said escapement to release said carriage, a stop-frame having a stop movable into the path of said carriage, operative means on said frame for engaging one end of said pivoted lever, means for moving said stop-frame and tilting said pivoted lever, and a plurality of co-operative members, one on said pivoted lever and one on said frame for normally locking the pivoted lever against movement, said locking members being inoperative during engagement of said pivoted lever by 115 said operative means.

5. In a typewriting machine having a platen-carriage mounted for letter-space 120 125 130

movement, a rack for said carriage, an escapement co-operative with said rack to control said carriage movement, a pivoted lever for disengaging said rack from said escapement to release said carriage, a stop-frame having a stop movable into the path of said carriage, operative means on said frame for engaging one end of said pivoted lever, means for moving said stop-frame and tilting said pivoted lever, and a plurality of co-operative members, one on said pivoted lever and one on said frame, said members having inclined meeting portions calculated to normally lock the pivoted lever against movement and to release said pivoted lever before its engagement with said operative means.

6. In a typewriting machine having a platen-carriage mounted for letter-space movement, a rack for said carriage, an escapement co-operative with said rack to control said carriage movement, a pivoted lever for disengaging said rack from said escapement to release said carriage, a stop-frame having a stop movable into the path of said carriage, an operating finger on said frame for engaging one end of said pivoted lever, tabulator-key-operated means for moving said stop-frame and causing said operating finger to tilt said pivoted lever, and a plu-

rality of fingers, one on said pivoted lever and one on said frame, for normally locking the pivoted lever against movement, said locking fingers being rendered inoperative before said operating finger actuates said pivoted lever.

7. In a typewriting machine having a platen-carriage mounted for letter-space movement, a rack for said carriage, an escapement co-operative with said rack to control said carriage movement, a pivoted lever for disengaging said rack from said escapement to release said carriage, a stop-frame having a stop movable into the path of said carriage, an operating finger on said frame for engaging one end of said pivoted lever, tabulator-key-operated means for moving said stop-frame and causing said operating finger to tilt said pivoted lever, and a plurality of fingers, one on said pivoted lever and one on said frame, said locking fingers having inclined meeting portions calculated to normally lock said pivoted lever against said frame and to release said pivoted lever upon operation of said tabulator-key-operated means.
